United States Patent

Des. 236,993
Patented Sept. 30, 1975

236,993

CHESS BOARD OR THE LIKE

Howard C. Davis, 89 Getzville Road,
Snyder, N.Y. 14226

Filed Jan. 31, 1974, Ser. No. 438,223

Term of patent 7 years

Int. Cl. D21—01

U.S. Cl. D34—5 SS

Fig. 1.

Fig. 2.

Fig. 3.

FIG. 1 is a perspective view of a chess board or the like embodying my new design,

FIG. 2 is a top plan view thereof, and

FIG. 3 is a sectional view thereof, taken on line 3—3 of FIG. 2.

I claim:

The ornamental design for a chess board or the like, substantially as shown and described.
